COMBINATION CONDIMENT AND TOOTH-
PICK HOLDER AND DISPENSER

Orville F. Couchot, De Land, Fla.

Application August 5, 1949, Serial No. 108,808

4 Claims. (Cl. 222—130)

1

This invention relates to a novel salt and pepper holder and dispenser and toothpick container and dispenser primarily intended for table use and which may be conveniently utilized for dispensing either salt or pepper and for holding toothpicks so that they may be conveniently removed therefrom.

Still another object of the invention is to provide a device for the aforescribed purpose having a novel closure for yieldably engaging and closing an opening in the dispensing cap of either the salt or pepper shaker.

Various other objects and advantages of the invention will hereinafter become more fully apparent from the following description of the drawing, illustrating a presently preferred embodiment thereof, and wherein:

Figure 1 is a top plan view of the condiment and toothpick holder and dispenser;

Figure 2 is a sectional view thereof taken substantially along a plane as indicated by the line 2—2 of Figure 1;

Figure 3 is a cross sectional view taken substantially along a plane as indicated by the line 3—3 of Figure 1, and

Figure 4 is an enlarged fragmentary sectional view taken substantially along a plane as indicated by the line 4—4 of Figure 1.

Referring more specifically to the drawing, the condiment and toothpick holder and dispenser in its entirety is designated generally 5 and includes a body, designated generally 6 which may be formed of any suitable material which is relatively light in weight including glass or plastic or a lightweight metal. The body 6 is provided with a bottom surface 7 on which it is adapted to rest and has a portion 8 which extends upwardly to substantially above the level of another side portion or section 9 thereof. The portion 8 is provided with spaced relatively deep recesses 10 and 11 which open outwardly of the top surface 12 of said portion 8. Said body portion 8 is provided with integral annular upstanding flanges 13 which rise from the top surface thereof and which form extensions of the recesses 10 and 11. Said annular flanges 13 are externally threaded for receiving a movable closure cap 14 each of which is provided with a central dispensing opening 15. One of the recesses, for example the recess 10, is adapted to contain salt and the other recess 11 is adapted to contain pepper. Said recesses 10 and 11 can be filled by removing the closure caps 14 therefrom after which the closure caps are re-applied to the threaded flanges 13.

2

The body portion 9 is recessed to provide a relatively large chamber 16 which is open at its top and which is adapted to contain toothpicks and the outer wall 17 thereof is provided intermediate of its ends with a cutout or opening 18. The end walls of the chamber 16 are provided with upstanding aligned lugs 19 which are disposed near to but spaced from the body portion 8. The open top of the chamber 16 is closed by a cover 20 having notches 21 opening outwardly at the ends thereof for loosely receiving the lugs 19. The intermediate portion of the outer edge of the cover 20 is provided with a bevelled under surface 22, as seen in Figure 3.

The body portion 8 is provided intermediate of its ends and adjacent the body portion 9 with a bore 23 which opens outwardly of its top surface 12 and which extends downwardly therefrom and which opens at its lower end into a recess 24 in the bottom surface 7. Another, shorter bore 25, formed in the body portion 8, extends between said recess 24 and the chamber 16.

A contractile coiled spring 26 extends through the bore 23, through a portion of the recess 24, through the opening 25 and has one end disposed in the toothpick chamber 16 and which is fastened to a depending apertured ear 27 of the cover 20. The other end of the spring 26 which terminates adjacent the upper end of the bore 23 is fastened to an eye 28 which depends from a closure, designated generally 29. The closure 29 comprises a bar including a substantially straight end 30, an intermediate portion 31 which is disposed at an obtuse angle to said portion 30 and an opposite shorter end 32 which is disposed at an obtuse angle to the intermediate bar portion 31. The eye 28 depends from said end 32 and the terminal of the bar end 32 is adapted to rest on the top surface 12 which forms a fulcrum for the closure 29. The outer end of the bar portion 30 is provided with an integral depending projection 33 which is shaped and sized to removably engage and close either of the dispensing openings 15. Said bar portion 30 is also provided with an upstanding projection forming a finger grip 34.

From the foregoing it will be readily apparent that the spring 26 functions to retain the closure 29 and also the closure 20 yieldably in closed positions. To remove a toothpick from the toothpick chamber 16 in which the toothpicks are disposed in horizontal positions, the thumb and index finger may be inserted through the opening or cutout 18 with the index finger dis-

posed above the thumb for grasping a toothpick and the nail of the finger is pressed against the bevelled edge 22 so that as the toothpick is removed upwardly the closure 20 can be swung upwardly and with its inner longitudinal edge pivoting against the wall 35 of the body portion 8. After the toothpick has been removed, the spring 26 will return the closure 20 to its closed position as illustrated in Figure 3. The walls of the chamber 16 are disposed in upwardly diverging relationship so that the toothpicks, not shown, contained therein may be more readily removed individually without striking the end walls of the chamber 16.

It will be readily apparent that the closure 29 may close the dispensing opening 15 of either cap 14 so that either salt or pepper may be dispensed from the holder 5 by inverting it and shaking the contents from either the recess 10 or the recess 11 the opening 15 of whose cap 14 is exposed. The closure 30 may be moved from its position of Figure 2 in which it closes the recess 10 to a position for closing the cap of the recess 11 by lifting upwardly on the finger grip 34 for disengaging the projection 33 from the cap opening 15 and for causing the closure 30 to fulcrum by engagement of the outer end of its portion 32 with the top surface 12 of the body and against the action of the spring 26. The closure 29 may then be swung on said end to position the projection 33 over the opening 15 of the other cap 14 and the pressure of the spring 26 will urge said closure to swing downwardly for engaging the projection 33 in said last mentioned opening 15 to thereby expose the cap opening of the recess 10 and close the cap opening of the recess 11.

The opposite side of the body portion 8 is preferably recessed as seen at 36 and the corners thereof, remote to the toothpick chamber 16 are preferably bevelled, as seen at 37 to reduce the weight of the holder 5.

Various modifications and changes are contemplated and may obviously be resorted to, without departing from the spirit or scope of the invention as hereinafter defined by the appended claims.

I claim as my invention:

1. A condiment and toothpick holder comprising a body having upwardly opening recesses adapted to contain salt and pepper, removable caps for normally closing the open tops of said recesses and each provided with a dispensing opening, said body having an upwardly opening

toothpick receiving recess terminating below the level of the open tops of said salt and pepper containing recesses, a closure swingably and detachably mounted on said body for closing the toothpick receiving recess, a closure member fulcrumed on said body for selectively closing the dispensing openings of either of said caps, said body having communicating passages, and a contractile spring disposed in said passages and fastened at one end to the toothpick recess closure and at its opposite end to said cap closure for yieldably retaining the closures in closed positions.

2. A holder as in claim 1, said toothpick recess having an outer wall provided with an opening adapted to receive the thumb and finger for engaging a toothpick and for extracting it from the toothpick recess when the closure thereof is swung upwardly.

3. A condiment holder having an externally threaded upper end, a cap threadedly engaging and removably mounted on said upper end, said cap being provided with a dispensing opening, a closure having a projection depending from one end thereof for engaging and closing said dispensing opening, said closure having a downwardly offset opposite end bearing loosely upon and fulcrumed on a portion of the holder, a contractile coiled spring disposed in the holder and having one end secured to said closure adjacent the last mentioned end thereof for yieldably urging the closure downwardly for holding said projection in engagement with the opening, said closure being adapted to be manually engaged and swung upwardly on said downwardly offset end as a fulcrum for disengaging the projection from the cap opening.

4. A condiment holder and dispenser as in claim 3, said closure comprising a bar having one end provided with said projection, the other end of said bar, which fulcrums on the holder, being disposed at an oblique angle to said first mentioned end whereby the outer end portion only thereof will bear against the holder.

ORVILLE F. COUCHOT.
